CLAIM

The ornamental design for a tree base cover, as shown and described.

DESCRIPTION

FIG. 1 is a top, front perspective view of a tree base cover showing our new design, shown in a connected state to a trunk shown in broken lines;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is another front view thereof, shown in a used condition attached to an extension piece and tree shown in broken lines;

FIG. 9 is a top, front, exploded, perspective view thereof;

FIG. 10 is a front exploded view thereof;

FIG. 11 is a right side exploded view thereof;

FIG. 12 is another front view thereof, shown in a non-connected state with the trunk shown in broken lines removed for ease of illustration; and,

FIG. 13 is a back view of FIG. 12.

The dashed broken lines depict portions of the tree base cover or environment of the tree base cover that form no part of the claimed design.

1 Claim, 13 Drawing Sheets
